UNITED STATES PATENT OFFICE.

LYMAN H. NELSON, OF PORTLAND, MAINE.

WRITING-PAPER TABLET.

No. 848,680.

Specification of Letters Patent.

Patented April 2, 1907.

Application filed May 11, 1906. Serial No. 316,256.

To all whom it may concern:

Be it known that I, LYMAN H. NELSON, a citizen of the United States of America, and a resident of Portland, Maine, have invented 5 certain new and useful Improvements in Writing-Paper Tablets, of which the following is a specification.

My invention relates to the manufacture of pads or tablets of writing or other paper, such as are commonly sold in stationery-stores, news-stands, &c. Such pads or writing-tablets are commonly made up of a plurality of sheets assembled and formed into a block, one end of which is secured by glue or cement to a cloth binder which overlaps the 10 end of the block and is secured on each side of the block to a cover composed of a single cardboard-sheet. The individual sheets being simply glued by one end to the binder are 15 readily pulled out, as required. Writing-paper is prepared and sold in large quantities in such pads, and the upper cover is frequently 20 decorated with some fancy design, giving the pad the appearance of an oblong book opening at one end. This construction answers 25 very well when the sheets are of thin flexible paper, or even when thick paper is used if the latter is handled with great care and the sheets simply torn off one at a time beginning 30 at the top; but when the sheets are opened up in the body of the pad or book or the pad is accidentally dropped or otherwise 35 roughly handled the edges of the sheets, which are glued to the binder, will immediately pull off and the book will fall to pieces. The reason for this is that the paper being 40 heavy and not easily bent and being attached to the binder by the edge only there is a leverage exerted at the edge tending to break it away when the sheet is bent. Many of these 45 pads are now made with heavy paper, each sheet of which has a souvenir picture or design, and when these pads are exposed for sale the public frequently open them up to examine them, and they immediately fall to pieces and are spoiled. This fault with the 50 pads as now made is a serious one and practically prohibits the sale of souvenir writing-paper when the paper has any considerable weight or body.

The object of my invention is to bind a plurality of sheets of writing-paper having considerable body or thickness into a pad or book, securing the attached ends of the sheets 55 to the binder so that they may be readily de-

tached to leave a clean edge and yet holding them strongly enough so that the pad or book may be opened and manipulated to a reasonable extent for the purpose of inspection without falling apart. 60

The invention consists, broadly, of a paper tablet containing a plurality of sheets of paper placed together to form a pad or block of removable sheets having a stepped construction constituting one beveled end with a continuous coating of adhesive material on said beveled end which covers the end and one adjacent face of each sheet and fills the angular recess between the ends, and in connection with this construction I preferably use a 65 binder of cloth or other flexible material. By this construction each sheet gets a coating of glue not only on its extreme edge, but also for a short distance in on the under side adjacent to the edge, so that it is held in an 70 angle of glue which adheres to the edge and under side. As a result, when one of the sheets is bent upward the pull which tends to detach it is parallel with the cemented surface on its under side instead of pulling directly away, as it does when only the edge is 75 attached by the glue. By forming the pad or book in this way I do not add anything to the cost of construction. I get a pad which is far stronger than the old construction and 80 capable of being opened up and manipulated to considerable extent without coming apart. I am thus enabled to put on the market heavy 85 souvenir letter-paper without danger of having the same spoiled by examination of 90 would-be purchasers.

I illustrate my invention by means of the accompanying drawings, in which—

Figure 1 is a perspective view of a pad or book constructed according to my invention. Fig. 2 is an enlarged section through the back edge, and Fig. 3 is a side elevation. 95

The pad or block A is made up of a plurality of sheets a of writing-paper or other paper which it is desired to form into book 100 form, while being at the same time easily detachable. At the end of the pad which is to be formed the ends of the sheets are "fanned" or shingled, so that they overlap or offset each other from the bottom upward, forming 105 a beveled end to the pad, which slopes from the bottom backward and upward. I find in practice that the best results are attained by making the inclination or bevel about forty-five degrees from the perpendicular. 110

To this beveled end is secured the cloth or other binder *c* in the usual way by the use of glue or other suitable cementing material, a thickness of cheese-cloth *c'* being inserted 5 between the binder proper and the glue, as here shown, although the binder may be glued directly onto the back of the sheets. As a result of this construction, it will be seen that the extreme end of each sheet and 10 a short section *d'* of the sheet adjacent to the under side, as shown in Fig. 2, will be found adhering to the binder *c*, and any tendency to bend one of the sheets upward will be resisted by the adhesion of the under surface, 15 and the pull will be a pull in the line of adhesion, as explained. A lower cover *b'* and an upper cover *B* are applied in the usual way by bringing the edges of the binder *c* around the corners and cementing them onto 20 the covers.

In order to make the pad more stable and less liable to break away at the top, I score the upper cover at *b* parallel with the back edge and in front of the overlapping edge of 25 the binder, so that when the cover is opened the joint will come at that point and not at the back edge.

It is evident that this method of binding may be used in binding books, pamphlets, 30 &c., when heavy paper is used, and it is applicable to a great variety of uses.

I claim—

1. The herein-described paper tablet consisting of a plurality of sheets of paper placed 35 together to form a pad or block of removable sheets having a stepped construction constituting one beveled end, a continuous coating of adhesive material on said beveled end which covers the ends and one adjacent face

of each sheet and fills the angular recesses 40 between the ends.

2. The herein-described paper tablet consisting of a plurality of sheets of paper placed together to form a pad or block of removable sheets having a stepped construction 45 constituting one beveled end and a binder having a flat adhering surface secured on said beveled end by adhesive material which coats the end of the pad and adheres to the end and adjacent portion of the face of each sheet 50 and fills the angular space between the sheets.

3. The herein-described paper tablet consisting of a plurality of sheets of paper placed together to form a pad or block of removable 55 sheets, the ends of the sheets at one end of the pad being arranged to offset or overlap each other from the bottom to the top to form a generally beveled end and a binder having a flat adhering surface secured to the 60 generally beveled end of the pad by an adhesive substance which coats the end of the pad and adheres to the end and to a portion of one adjacent face of each sheet and fills the angular spaces between the sheets.

4. The herein-described process of forming a pad or tablet of removable sheets which consists of assembling a plurality of sheets of paper to form a pad or block, "fanning" or offsetting the sheets at one end of the pad, 70 coating the end with adhesive material and finally applying a binder having a flat adhering surface to the offset end by means of said adhesive material.

LYMAN H. NELSON.
